BRAIDING MACHINE

William C. Wright, Granite Falls, N. C., assignor
to Samson Cordage Works, Boston, Mass., a
corporation of Massachusetts

Application September 9, 1940, Serial No. 356,014

6 Claims. (Cl. 96—3)

This invention relates to a braiding machine and more especially to one equipped with a combined oil circulating system and lint cleansing means. As a general rule, braiding machines employ very short staple cotton or other material for making ropes, cords and the like. As a result, there is a very heavy fall of lint, or loose fibers onto and into the machine. This waste not only presents an unsightly spectacle, but also presents a serious obstacle to healthful working conditions within the mill. Furthermore, the lint eventually accumulates in balls and clogs up the moving parts of the machine, making it expensive to clean and otherwise adversely affecting its operation.

The construction of most braiding machines is such that quite a number of moving parts are essential. These moving parts include suitable flyers, which are directed in a very irregular path. By so directing the flyers, it is possible to produce the proper braiding effect; however, there is a very decided amount of frictional engagement due to the abrupt turning of the flyers at certain times. Such a construction, therefore, makes it very essential that the proper lubricating system be provided so that the parts will operate with a minimum of wear and friction and also with a minimum amount of noise.

It is an object of this invention to provide a braiding machine equipped with a fluid circulating system which is adapted to wash the lint from the surfaces of the machine as it accumulates. This system is equipped with a suitable filtering mechanism which cleanses the fluid before it is recirculated over the machine surfaces. Although many suitable fluids may be employed for the purpose of removing the lint, it is preferable to use a lubricant, such as oil, so that the dual function of cleansing and lubrication will be simultaneously performed.

It is another object of this invention to provide an improved yarn carrier for the braiding machine which has means for supporting a yarn package during a braiding operation, which package has a strand emanating therefrom and leading to the material which is being braided such as a rope or the like. This improved carrier has means for maintaining a substantially constant tension on the strand at all times, as it is fed from the package. Also means are connected with this carrier for releasing this tension applying means so that the package can be freely rotated reversely or forwardly when desired. For example, when a strand becomes broken and it is necessary to provide additional slack in the

strand for tying purposes, hence the package must be reversely rotated a small amount.

It is a further object of this invention to provide an improved carrier of the class described which has means operated by the strand emanating from the package, for automatically applying the let-off mechanism when a predetermined amount of tension has been applied to the strand. When the let-off control is placed in an inoperative position so that a broken strand can be tied, it is only necessary to turn the package reversely until a predetermined tension is applied to the mended strand and this tension will automatically place the let-off mechanism in operation.

Some of the objects of the invention having been stated, other objects will appear as the description proceeds, when taken in connection with the accompanying drawings, in which—

Figure 1 is a sectional plan view of a braiding machine made in accordance with the present invention, with certain portions thereof broken away and other portions thereof shown in section;

Figure 2 is a vertical sectional view through an improved carrier employed in the present invention and taken along the line 2—2 in Figure 1;

Figure 3 is a vertical sectional view taken along the lines 3—3 in Figures 1 and 2;

Figure 4 is a vertical sectional detail view taken along the line 4—4 in Figure 2;

Figure 5 is an enlarged vertical sectional view similar to the lower portion of Figure 4, showing the means for latching the tension let-off mechanism out of operative position;

Figure 6 is a sectional plan view taken along the line 6—6 in Figure 2;

Figure 7 is a longitudinal vertical sectional view taken along the line 7—7 in Figure 1;

Figure 8 is a sectional plan view through the pump mechanism and taken along the line 8—8 in Figure 7;

Figure 9 is a transverse vertical sectional view taken along the line 9—9 in Figure 1.

Referring more specifically to the drawings, the numeral 10 denotes a housing for a braiding machine, said housing having a hollow post 11 secured to the central portion thereof by any suitable means such as screws 12. The hub member 16 is rotatably mounted around the post 11 and this hub has radially disposed prongs 17 extending therefrom. The outer ends of these prongs have slots 18 disposed therein for fitting around spacer bolts 19 which are employed for holding plate and gear members 20 and 21 on the upper and lower sides respectively, of the hub 16. In

other words, the members 16 and 17 serve as a uniting bar to cause the members 20 and 21 to rotate as a unit about the post 11. In order to reduce the friction between the hub member 16 and the post 11, suitable ball bearings 14 and 15 are provided.

The member 21 is a large gear disposed near the lower portion of the housing 12 and operates the carriers during a braiding operation to cause them to travel in a predetermined path. This gear 21 is secured around the lower portion of the hub 16, and the teeth therein mesh with a gear 25, which gear is rotatably mounted around a vertically disposed spindle 26 (Figures 1 and 7). The hub of the gear 25 has a beveled gear 27 fixedly secured thereon. This gear meshes with another beveled gear 28 on shaft 29 (see Figure 1), said shaft being rotatably mounted in a bearing 30, which in turn extends to the exterior of the housing 10.

Upon the projecting end of bearing 30, a suitable loose pulley 32 is rotatably mounted and upon the projecting end of shaft 29 a fixed pulley 33 is mounted alongside pulley 32. Also a hand wheel 34 is mounted on the end of shaft 29. A suitable belt, not shown, is adapted to be placed on the fixed pulley when the machine is in operation. This belt may be shifted to the loose pulley 32 when desired, to stop the braiding machine, but at the same time allow the belt and the driving means therefor to continue operating. It is, therefore, seen that when the fixed pulley 33 is in motion, the members 29, 28, 27, 25 and 21 will rotate.

The upper portion of the gear 21 has a plurality of studs 37 threadably secured therein, each of the studs being disposed on a common circle whose center is post 11, which post is the axis of rotation of the gear. Each of the studs 37 has a sleeve 38 mounted therearound, said sleeve having integral with the upper end thereof, a cam 39. Rotatably mounted around the sleeve 38 is a horn gear 40 which has a plurality of notches 41 in the periphery thereof. This horn gear is secured to the lower face of a pinion or gear 51, which meshes with the teeth in a ring gear 52, said ring gear being secured to the inner wall of the housing 10 by any suitable means such as bolts 54. Suitable notches 42 are cut in the periphery of gear 51 for coinciding with notches 40 in the horn gear.

The bolt 54 also slidably penetrates an externally threaded sleeve 55. This sleeve 55 is threadably secured in a top ring 56 which is disposed directly above the ring gear 52. The purpose of providing the threaded sleeve 55 is to facilitate easy adjustment of the elevation of the top ring 56. It is evident that it will be necessary to turn the sleeve 55 so as to vary the distance the lower end thereof projects beneath the plate 56. Since the lower end of the sleeve 55 rests on top of the annular internal gear 52, the height or elevation of the top plate will be determined by this projecting portion.

Each of the studs 37 forms a center for a circular groove 60 in the top surface of gear plate 21. The groove 60 is adapted to accommodate a crescent shaped projection 61 on the lower end of a carrier assembly broadly designated by the reference character 62. The groove 60 also communicates with a circular groove 63 in gear plate 21 which has its center about the post 11. During a braiding operation, the projections 61 are adapted to travel in grooves 60 and 63 so that the proper motion will be imparted to the flyer

5 to effect a braiding operation. This movement of the flyers is generally known in the trade although so far as I am aware the specific arrangement of the parts and the specific structure employed for performing this movement is new.

The crescent-shaped projection 61 has integral with the upper portion thereof, a rounded portion 66. This rounded portion is adapted to travel directly above the groove 63, and as it approaches the groove 60, it is engaged by one of the horns 68 of the horn gear 40. Between the horns 68, the notch 41 is formed which accommodates this rounded portion. The coinciding notch 42 in gear 51 simultaneously receives the rounded portion. While in these notches, the rounded portion, along with the carrier is caused to follow the groove 60 until it again emerges into the groove 63, where it is deposited in one of the notches 69 in the ring gear 52.

20 While the flyer 62 is rotating about the stud 37, the plate or gear 21 together with studs 37, horn gears 40, top plate 20, gears 51 are bodily rotating about the upstanding post 11 as an axis. It should be noted, however, that the rounded portion 66 of each of the flyers is adapted to rest in the notches 69 in the inner face of the ring gear 52, when it is not following groove 60. By observing Figure 1, it will be seen that there are 25 twelve equally spaced notches 69 in the ring gear 52, therefore, during the operation of the machine, two-thirds of the carriers 62 are adapted to be arrested by the notches 69 while the other one-third of the carriers are being rotated around the groove 60. In other words, the horn gear 40 and pinion 51 rotate a carrier around the groove 60 and then deposit it in one of the notches 69 in the ring gear. Then the horn picks up another carrier which is in a notch 69 and causes this carrier to be rotated about this same groove as 30 in the previous case. In the present embodiment of the invention, there are four sets of carriers with three flyers per set. The operation of each set is identical. In other words, there are always 35 two carriers idle while the third carrier is in motion.

40 Disposed directly above the rounded portion 66 of each carrier is a laterally extending flange 79, which flange is adapted to slide beneath top plate 20 and top ring 56 in the manner shown in Figures 1 and 7. Adjoining the flange and extending upwardly therefrom, substantially in alignment with portions 61 and 66, is a second crescent-shaped portion 71, this crescent shaped portion being adapted to operate in annular groove 72 which is provided between the top ring 56 and the top plate 20. Groove 72 has its center 45 about the axis of rotation of plate 20, namely post 11. The groove 72 communicates with smaller circular grooves 73 which are disposed between the peripheries of cam 39 and the top plate 20. The crescent-shaped portion 71 is similar to the crescent-shaped portion 61 and operates substantially in the same manner in grooves 72 and 73 as the portion 61 operates in the grooves 60 and 63. The upper part of the crescent-shaped portion 72 has a laterally extending base 76, upon which is bolted a bracket member 77. Bracket 77 is secured to the base 76 by any suitable means such as stud bolts 78 (see Figure 2). Both the base 76 and the bracket 77 are flush bottom so that a flat surface will slide upon the upper surface of top ring 56 and top plate 20. Due to the fact that there is considerable contact surface between the carrier assembly 62 and the operating parts it stands

to reason that ample lubrication should be provided in order to prevent excessive wear.

The bracket 77 of the flyer assembly 62 has a pipe 80 extending upwardly therefrom, which pipe forms a spindle around which a second pipe 81 is adapted to rotate. This second pipe has a disk 82 secured to the lower portion thereof, said disk having upstanding projections 83 for fitting into notches 84 of spools 85. Around the spool 85, suitable cordage, yarn, or other strand material 86 is adapted to be wound. The strands emanating from these packages are designated by reference character 87.

It will be noted by referring to Figures 2 to 6 inclusive that the disk 82 has a circular row of teeth 88 on the upper side thereof. The purpose of these teeth is to accommodate the pointed end 89a of a dog 89, which dog is pivoted as at 90 to bracket 77. The end of dog remote from end 89a is normally pushed upwardly, by means of a suitable collar 91 and a compression spring 92. This compression spring normally tends to hold the pointed end 89a of the dog 89 yieldingly in engagement with the teeth 88 of the ratchet and thereby offer a resistance to the let-off of the strand 87 from the package 86.

The spring 92 and the collar 91 are mounted around a vertically disposed pin 93, said pin having a ball 94 on the lower end thereof which is anchored in the bracket 77 (Figure 3). This ball permits a limited universal movement of the upper end of the pin 93, and since the dog 89 swings about the pivot 90, it is seen that certain amount of lateral movement of the upper end of pin 93 will be necessary to prevent binding.

The upper end of the pipe 81, as well as the upper end of spool 85 is held in position by means of a suitable arm 95. This arm has integral therewith a projection 96 which fits downwardly into the upper end of the pipe 81. The other end of arm 95 is pivotally secured to the upper portion of a second pipe 99, said second pipe having its lower end secured to the bracket 77. The members 95 and 99 serve to support the top of the spool 85 to prevent tilting while in operation.

The pivotal connection for the arm 95 comprises a bolt 100, extending downwardly into pipe 99 from the arm, said bolt having a head 101 on the lower end thereof which also fits on the interior of the pipe. The bolt 100 slidably penetrates a washer 102, secured in the upper end of the pipe 99 by any suitable means such as a screw 103. A spring 104 is disposed around the bolt 100 between the head portion 101 and the washer 102, so that the arm 95 will normally be pulled downwardly at all times to bold line position as shown in Figure 2. When it is desired to insert or remove the spool 85 on the pipe 81 it is only necessary to raise the arm 95 to dotted line position as shown in Figure 2, and then impart rotative movement to the free end thereof, thus providing ample space for inserting or removing a package of yarn around the pipe 81. This type of construction enables the let-off to be controlled from the lower side of the package of yarn and also permits the let-off mechanism to be entirely independent from the spool 85. In other words, the conventional spool 85 can be employed with this type of mechanism without making any changes therein.

The strand 87 which emanates from the package of yarn or other material 86 passes around the pipe 99 in the manner shown in Figures 3

and 7 and then into engagement with a suitable yarn guide member 108, fixedly secured around the pipe 99. The strand then passes downwardly beneath a grooved circular guide 109, which is secured to a vertically disposed rod 110, said rod being mounted for vertical sliding movement in the lower portion of pipe 99.

The grooved member 109 has integral therewith, a flat elongated projection 109a, which is adapted to slidably penetrate a vertically disposed slot 99a in pipe 99. The base of the projecting portion 109a fits into a groove of keyway 115, cut lengthwise in the shaft 110. This groove has varying depths for reasons which will hereinafter be described. In order to secure the member 109 to the pipe or rod 110, a suitable screw 111 is employed.

The rod 110 has a restricted portion 116 extending upwardly therefrom and within the hollow pipe 99. The upper end of this restricted portion slidably penetrates a washer 117, said washer being fixedly secured in the pipe by any suitable means such as screw 118. In order to limit the downward movement of the restricted portion 116, and the rod 110, a suitable collar 119 is provided on the upper end of restricted portion 116 at a point above washer 117. Also disposed around the restricted portion 116 between rod 110 and washer 117 is a compression spring 120 for normally forcing the rod 110 downwardly within the pipe 99 until collar 119 engages fixed washer 117. The tension in strand 87, however, normally compresses the spring 120 and causes the portion 119 to be disposed a substantial distance above fixed collar 117.

By observing Figure 5, it will be seen that the grooved member 109 has a notch 121 in the lower edge thereof, said notch being adapted to be engaged by prong 89b of dog 89. In the bold line position as shown in Figure 5, the upper end of the prong 89b rests in the notch 121 and thereby holds the member 89 in tilted position, so that the end 89a will not engage the teeth 88. With the members 89 and 89b in the tilted position as shown in Figure 5, the teeth 88, disk 82, spool 85 and yarn package 86 are free to rotate about the pipe 80; therefore, the strand 87 which emanates from the package 86 can be wound or unwound therefrom as desired, without any resistance being offered. Although the spring 92 (Figure 3) has a tendency to rotate the latched dog 89 in a clockwise manner in Figure 5 to cause the dog point 89a to engage teeth 88, this rotation will not take place because of the peculiar shape of notch 121. However, it should be noted that when the grooved member 109 and its associated notch 121 are lifted slightly upwardly by the tension in strand 87, the spring 89b will be released from the notch and thereafter the member 89 will resume the dotted line position as shown in Figure 5 due to the upward pressure of the compression spring 92 (Figure 3).

As heretofore stated, the strand 87 passes from package 86 around pipe 99, then downwardly through groove 108a in guide member 108, then around the under side of grooved member 109, then upwardly again through groove 108a and then through eyelet 126 in member 90. From the eyelet 126, the strand 87 passes to bracket 128, said bracket having a hole 128 in its central portion through which a finished braided rope or cord 129 is adapted to pass. The rope comprises a plurality of strands 87 which emanate from carriers 62. These strands are braided

around a center strand 130, said center strand being adapted to pass upwardly through the center of post 111. This post is provided with a suitable pipe 131 in the central portion thereof for the accommodation of this center strand. During operation of the machine, this center strand passes at the proper speed upwardly while the strands 87 are being braided therearound, thereby encasing the same within the tubular fabric to form a cord or rope.

The bracket 128 is supported by a rod 133 which rod is slidably and adjustably mounted in lug 134 by any suitable means such as set screw 135. Lug 134 forms an integral part of an inverted L-shaped bracket 136, the lower end of said bracket being secured to the housing 10. After the rope 129 has been braided, it passes around suitable rollers 137 and 138 which are mounted upon shafts 139 and 140, respectively. Shafts 139 and 140 have pinions 141 and 142, respectively, mounted thereon, said pinions being connected to each other by means of an intermediate pinion 143. Another roller 144 is provided which rests directly upon the braided rope 129 and above the roller 138, so that the necessary gripping action will be effected. This roller 144 is positively driven through the medium of gears 143, 145 and 146.

A train of gears, namely, 147, 148, 149, 150 and 151 are connected to the gear 142. Gear 151 meshes with a suitable worm 153 on the upper end of a vertically disposed shaft 154, said shaft 154 extending downwardly on the interior of the housing 10, and having fixedly secured on the lower end thereof, a gear 155. This gear 155 meshes with gear 25, previously described. It is therefore seen that as the fixed pulley 33 is rotated, in Figure 1, that the cord or braided rope 129 will be positively drawn upwardly through the medium of the parts indicated by reference characters 137 to 155 inclusive.

One of the very important features in the improved type of carrier, is the means for latching and unlatching the let-off means out of and in operation respectively, so that the package of yarn or cordage 86 can be rotated in the desired direction without any obstruction. For example, let us suppose that one of the strands 87 becomes broken and it is necessary to have additional slack in order to tie the two broken ends together. It is only necessary for the operator to take the broken end of the strand which is connected to the package 86 and pull the same, and this pull will cause the package 86 to rotate to let-off additional length. When rotated in this manner, the pointed end 89a on the dog 89 will ratchet over the teeth 88 thereby causing a greater length of strand 87 to be available at a point beyond the eyelet 122. After the strand has been tied in, there is an excess of slack and it is then desired to rewind the slack portion back upon the package 86 so that the proper tension will be present. In order to do this, it is necessary to press upon the left-hand end of the dog 89, and cause it to move from the dotted line position, as shown in Figure 5, to the bold line position at which time the lower edge of portion 109a of the grooved member 109 will be engaged to thereby move the members 109 and 110 upwardly a slight amount against the downward pressure of spring 120. After a very slight upward movement the free end of the prong 89b will fall into the notch 21 and become latched in this position. At

this time, the point 89a will be disengaged and the operator can turn the package 86 in the proper direction to cause the slack strand 87 to be wound back upon the package.

When the braiding machine is started in operation and when a predetermined amount of tension has been created in the re-tied strand, the members 109 and 110 will be pulled slightly upwardly, thereby releasing the free end of 10 prong 89b to allow the spring 92 to force the pointed end 89a into engagement with teeth 88, after which the let-off means for the package is in operation.

During the operation of the carrier there is 15 sufficient tension in the strand 87 to cause the rod 110, restricted portion 116 and members 119 to be slightly elevated so that portion 119 will be disposed a substantial distance above collar 117. In fact, the members 110, 116 and 119 20 reciprocate up and down in pipe 99 during the rotation of the carrier, so that there will not be any slack between eyelet 126 and hole 128a (see Figure 7). When a strand 87 breaks the tension is released and as a consequence, the spring 25 120 will force members 110 and 116 downwardly until portion 119 engages stationary collar 117. When in this lowermost position, the lower end of rod 110 will engage a stop motion, not shown, 30 to stop the machine. The foregoing description relates to a braiding machine of the circular orbit type.

Another very essential part of the invention is the dirt, dust and lint removing means for keeping the exposed surfaces of the braiding 35 machine free from these substances. In the present embodiment of the invention, I have devised an oil circulating system which will spray the oil upon the top portions of the braiding machine and keep the lint and waste removed as fast as it accumulates. In addition to the fact that the lint and waste will be removed, there is the added advantage of having the oil continuously lubricate all of the parts while the machine is running, thereby causing 40 the machine to operate with greater efficiency, less wear on the parts and less noise.

The housing 10 is provided with a pair of wells 160 and 161 which wells are adapted to receive a suitable lubricant or other cleansing 50 fluid 162. The lower end of these wells all connect by means of a pipe 163. In order to provide a suitable outlet for this oil when draining the wells, suitable plugs 164 and 165 are provided in the lower ends of wells 160 and 161 55 respectively. The upper end of well 161 is open and communicates with the interior of the housing 10 by way of opening 166 (see Figure 9). The oil which drains from the moving parts within the housing 10 passes through the opening 166 and downwardly into the well 161.

A suitable filter 167 is disposed in the upper portion of the well 161 so that any impurities such as lint, dirt, dust, filings and grit which have been collected by the oil, as it passes through the machine, will be retained thereby allowing the oil to pass to the bottom of the well 161 and then through pipe 163 into the well 160.

Well 160 has a pump housing 170 disposed therein (see Figures 7, 8 and 9) the lower portion of said housing being closed by a nut 172. A block 173 is adapted to fit inside housing 170, said block having gears 174, and 175 fitting therein and being adapted to mesh with each other. The extremities of the teeth of the gears

174 and 175 press snugly against the interior bore in which these pinions are located in a well known manner. Leading into the block 173 is an intake port 176 which permits the oil or other fluid to be drawn from the lower portion of well 160 to the interior of the block and into contact with the teeth of gears 174 and 175. As the gears turn, the oil is carried around to a suitable outlet port 177 which expels the oil into the interior of casing 170.

It will be noted by referring to Figure 7, that a shaft 179 extends upwardly from the gear 175 and within a restricted portion 170a of housing 170. This restricted portion encases the shaft 179 so that a proper annular clearance 181 will exist between the shaft and the interior of the restricted portion to permit a flow of oil therethrough. The upper end of the shaft 179, however, is enlarged as at 179a, thereby completely filling up the upper end of the restricted portion 170a so as to prevent the oil from escaping from the upper end. Upon the upper portion of the shaft 179a, a pinion 180 is secured, which pinion meshes with gear 155 previously described, which furnishes the driving means for the gear pump.

Communicating with the upper portion of clearance 181 around the pipe 179, is one end of a pipe 182. The other end of said pipe leads to an annular bore 183 which is disposed between post 11 and pipe 131 (see Figure 7). The upper end of the annular bore 183 has leading therefrom a plurality of radially disposed nozzles 184 for directing the fluid which is under pressure within the pipe 82 and within the bore 183 out upon the top plate 20 so that the lint and other waste which accumulates thereon will be washed away during the operation of the machine. Since the carriers 62 substantially follow the grooves 72 and 73, between the plates 20 and 56, it is seen that the bracket portion 77 will sweep a considerable surface thereof free from the waste. Especially is this true if there is an oil film disposed thereover. In addition to the lint removing factor, there is an added advantage of having filtered oil circulate and recirculate through the machine at all times. Some of the oil which is expelled on the top plate 20 is transferred to the top of plate 56 by the movement of the carriers and thereafter is allowed to pass downwardly among the moving parts of the machine to lubricate the same, after which the oil flows out of housing 10 through opening 166, and downwardly through filter 167 into well 161. The well 160 has a cover 178 to prevent the return of unfiltered oil to this well.

In order to vary the force at which the oil is expelled through nozzles 184 into the members 20 and 56, a suitable outflow pipe 190 is provided, said pipe having a petcock 191 disposed on the upper end thereof which may be turned to the desired angle to permit portions of the oil which is forced upwardly into this pipe to escape into the housing 10. In other words, the degree to which the petcock 191 is opened, will determine the amount of pressure which is present in the pipe line 182. If it is desired to have a minimum amount of oil pressure at the nozzles 184, then the petcock 191 will be opened the maximum amount to allow a greater portion of the oil which has been forced through the oil pump to escape before it reaches nozzles 184.

Another very important factor in this invention is the position and function served by the disk member 82. This member not only serves as a means for supporting the ratchet teeth 88 to serve

as a let-off mechanism, but also serves as a shield for protecting the lower portion of the yarn package 86 from the oil which is expelled from the nozzles 184. Since the nozzles are located at a lower elevation than the disk 82, it is seen that the expelled oil will not in any way gain access to the yarn thereabove.

By actual tests, the above described lubrication and cleansing system has been found to materially decrease the noise, the wear of parts and the operating costs. Furthermore, the parts are so positioned in the machine that the oil will fall by gravity on all wearing parts within the housing 10 after it has been expelled from nozzles 184 thereabove, thus insuring proper lubrication without the necessity of having an extensive piping arrangement.

Another very important feature of the machine is the manner in which the parts in housing 10 are assembled or dismantled. It is only necessary to remove bolts 19, 37 and 54, and then the entire works can be lifted, piece by piece, out of the housing.

In the drawings and specification, there has been set forth a preferred embodiment of the invention, and although specific terms are employed, they are used in a generic and descriptive sense only and not for purposes of limitation, the scope of the invention being set forth in the appended claims.

I claim:

1. In a machine for braiding a cord and the like, having a plurality of strand carriers and having means for rotating all of said carriers bodily about a common axis, and also having means for rotating each of said carriers individually about its own axis, a housing encasing said rotating means, a fluid supply, a filter for the fluid, and means for continuously forcing said fluid into said housing over said rotating means, through said filter and back to the fluid supply to thereby keep the parts free from accumulated lint, grit, waste and the like.

2. In a braiding machine having a plurality of carriers, each of said carriers having a package thereon from which a strand is drawn for braiding cord and the like, means engaging the base of said carriers for rotating them about a common vertical axis during a braiding operation, a fluid supply, means for directing said fluid over said carrier rotating means to thereby keep the parts free from lint, grit, dust and the like, and means disposed between the base of each package and the carrier rotating means for preventing said fluid from contacting the package.

3. In a braiding machine having a plurality of carriers, each of said carriers having a package thereon from which a strand is drawn for braiding cord and the like, means engaging the base of said carriers for rotating them about a common vertical axis during a braiding operation, a fluid supply, a filter for the fluid, means for directing said fluid over said carrier rotating means, through said filter and back to the fluid supply, to thereby keep the parts free from lint, grit, dust and the like, and means disposed between the base of each package and the carrier rotating means for preventing said fluid from contacting the package.

4. A braiding machine comprising a plurality of strand carriers, means for rotating said carriers about a common axis during a braiding operation, a fluid supply, a conduit between said supply and said axis, means for directing the flow of fluid from the conduit radially from the

axis and over the rotating means, and means for pumping the fluid from said supply through the conduit and over the rotating means.

5. A braiding machine comprising a plurality of strand carriers, means for rotating said carriers about a common axis during a braiding operation, a fluid supply, a filter for the fluid, and means for circulating and recirculating said fluid over said rotating means through said filter and back to said fluid supply.

6. A lubrication and lint removing system for

a braiding machine of the circular orbit type, said machine having strand carriers, means disposed around said orbit for actuating said carriers during a braiding operation, comprising an oil supply, means for directing said oil over said carrier actuating mechanism to thereby keep the parts lubricated and to keep the lint removed therefrom, and means for filtering said oil to remove the lint therefrom, and means for returning the filtered oil to said supply.

WILLIAM C. WRIGHT.
